BARK SCRAPING MACHINE

Filed Sept. 24, 1947

UNITED STATES PATENT OFFICE

2,547,785

BARK SCRAPPING MACHINE

Anthony P. Savickas, Boynton Beach, Fla.

Application September 24, 1947, Serial No. 775,812

1 Claim. (Cl. 144—207)

1

This invention relates to an improvement in scraping machines and has particular reference to a debarking device.

It is an object of the present invention to provide a machine the characteristics of which are to completely and gently remove the bark from those types of wood having a relatively thin layer, without injury to the fibers of the wood, and to leave a highly finished surface free from marks of the scrapers employed.

A further object of the invention resides in the provision of a machine which will remove the relatively thin bark in extremely close grained woods, such as bamboo, without marring the exposed wood surface, and which will follow all irregular surfaces, cleaning off the bark completely and leaving the irregular surfaces completely cleaned and exposed in order not to detract from the desired ornamental appearance of the wood and the articles to be manufactured therefrom.

Another object of the invention resides in the extreme simplicity of the device, possessing few and simple parts that are easily and quickly replaced in the event of breakage, is strong, durable, cheap to manufacture and so constructed and operated as to minimize bodily danger if accidentally contacted by the operator while in use.

It is a well known fact that in the manufacture of wood articles from such material as bamboo, it is essential, in order to produce an article capable of maintaining its original bright color against staining or discoloring, that the bark be first removed in order for the extremely close grained body of the wood to season naturally. Also, it has been found that the removal of the bark by hand scraping or sanding is both tedious and expensive and fails to produce a surface free of scraper marks, sander marks and other irregular surface marks and thus makes the wood undesirable for manufacturing purposes, with the result that manufacturers have a tendency to manufacture articles from the wood without removing the bark. Bamboo articles manufactured without first removing the bark soon become discolored, getting dark in color and losing the desirable bright color attainable when the bark is removed and the wood permitted to properly season. It is with these highly objectionable features in mind that the simplified method of debarking as hereinafter described was conceived, this method enabling an operator to debark in a few minutes a piece of bamboo that, if scraped by hand, would ordinarily require a couple of hours, and also enabling an operator to obtain a much

2

finer product than could be obtained by hand scraping.

Other important objects and advantages of the invention will be readily apparent during the course of the following description, reference being had to the accompanying drawings.

In the drawings:

Figure 1 is a side elevation of a machine constructed in accordance with the invention,

10 Figure 2 is a plan view thereof,

Figure 3 is a transverse section taken on line 3—3 of Figure 1,

15 Figure 4 is a fragmentary side elevation of a belt and scraper illustrating the manner in which the scrapers follow the irregularities of the wood surface,

Figure 5 is a section taken on line 5—5 of Figure 2,

20 Figure 6 is a perspective view of a modified form of scraper and,

Figure 7 is a further modified form of scraper.

Like numerals are employed to designate like parts throughout the several figures of the drawings.

25 Referring specifically to the drawings, the numeral 5 designates a suitable base member of any desired dimensions, having mounted upon one end thereof an upstanding bearing 6, fixed in a convenient manner upon the base, and at the opposite end of the base a bearing 7 is mounted. The bearing 7 is a conventional type, being adjustable in a horizontal plane. The bearing 6 rotatably supports a drive shaft 8, carrying at its outer end a relatively wide pulley 9 and at its opposite end a drive pulley 10, having connection with any desired source of power. The pulley 10 is of a predetermined diameter for proper speed of rotation of the pulley 9. The bearing 7 supports a shaft 11, upon the outer end of which is mounted an idler pulley 12. An endless belt 13 engages and travels with the pulleys 9 and 12, in the direction indicated by the arrow in Figure 1 and travels over a work table 14. The table is of a width corresponding to the width of the belt and has its ends terminating adjacent the pulleys 9 and 12. A work engaging fence 15 is carried by the work table for its entire length and is provided with a right angle head stop 16. The table and work fence are supported upon the base 5 by brackets 17. The belt 13 may be formed of any desirable material having strength and flexibility.

Mounted transversely of the belt 13, at equidistantly spaced points throughout its length, are 55 a plurality of scraper blades 18, formed of flex-

ible spring steel and having an upward and rearwardly inclined blade portion, the upper edge of which is sharpened at 19 throughout its length. The blade 18 is bent along a line 20 to a predetermined angle in order to provide an attaching leaf 21, engaging the belt for its entire width and held in fixed position upon the belt by suitable fastening devices 22, the heads of which are countersunk in the underside of the belt. Two such fastening devices have been illustrated for each blade, though more may be employed for larger blades employed in extra heavy duty work. The blade 18 flexes upon the bend line 20 in use, but certain flexing of the blade will also appear throughout the cutting portion of the blade when unusual irregularities in the surface being treated are encountered. As illustrated, the blades incline rearwardly from the line of travel, hence impart a gentle but definite scraping action upon the thin bark of the bamboo, the slight distortion of the belt and blade permitting conformation of the blade to the irregularities of the wood, see Figure 4, and imparting a scraping action to both the projections and indentations of the wood.

In the use of the invention, the belt is placed in motion, travelling in the direction of the arrow, at which time a section of the wood to be scraped is placed upon the scrapers, lying against the fence 15, with one terminal end engaging the head stop 16. A slight hand pressure upon the wood causes the blades to gradually remove the thin bark, while the operator slowly revolves the section of wood so that its entire surface will be evenly scraped. The head stop 16 prevents endwise movement of the wood under the scraping action of the blades. The blades are of such width as to accommodate sections of wood of varying diameters, as shown by dotted lines in Figure 3. The inclining of the blades away from the line of travel minimizes the danger to the operator in the event he should fall upon or accidentally bring his hands into contact with the blades.

In Figure 6 a modified form of blade has been illustrated at 23, having an attaching leaf 24 and an integral scraping blade section 25 bent therefrom along a line 26 to lend flexibility thereto. In this form of the invention, the blade is cut into sections 27, with the cuts terminating in enlarged openings 28. The sections 27 are provided with sharpened cutting edges 29. In this form of blade, the individual cutting sections 27 will permit variable flexing for contour scraping and for riding over and into the irregularities of the wood. The mounting and inclination of the blade 23 correspond to those of the blade 18.

In Figure 7, a further modified form of blade has been illustrated at 30, having an attaching leaf 31, integral with the inclined blade section

30 and bent therefrom along a predetermined line 32. The cutting edge 33, in this form of the invention has been formed concave to more readily engage a greater area of the wood section during its travel. The mounting and inclination of this blade also correspond to those of the blade 18.

All of the blades have their corners rounded, as shown, to avoid gouging or damaging of the wood fibers during the scraping operation and further to minimize danger to the operator when contacted.

It will be seen from the foregoing that an extremely simple and efficient machine has been provided to debark in a minimum of time thin skinned wood having unusually close fibers, without damaging the under surface of the wood. The machine as actually used has proven highly satisfactory and results in an enormous saving in labor. The parts are such as to require a minimum of attention and replacement costs have proven negligible.

It will of course be understood that the invention is not limited to the precise arrangement shown, but that it includes within its purview whatever changes fairly come within either the terms or the spirit of the appended claim.

Having described my invention, what I claim is:

In a debarking machine comprising a base, bearings carried by the base, shafts supported by the bearings, pulleys carried by the shafts, an endless belt supported upon the pulleys, a plurality of flexible scraping blades, positioned transversely of the belt, said blades inclined away from the direction of travel of the belt, a work table for supporting the upper flight of the belt, a work fence mounted on said base adjacent one side of said upper flight for maintaining work in scraping relation to the blades and a head stop carried by the fence and extending above and across said upper flight for retaining the work against longitudinal movement under the scraping action of the blades.

ANTHONY P. SAVICKAS.
